UNITED STATES PATENT OFFICE.

THOMAS MACKENZIE, OF GLASGOW, SCOTLAND, ASSIGNOR TO DAILUAINE TALISKER DISTILLERIES LIMITED, OF GLASGOW, SCOTLAND.

DESIGN FOR A GLASS BOTTLE.

46,285.

Specification for Design.

Patented Aug. 18, 1914.

Application filed June 15, 1914. Serial No. 845,313. Term of patent 14 years.

To all whom it may concern:

Be it known that I, THOMAS MACKENZIE, a subject of the King of Great Britain and Ireland, residing at No. 26 India street, Glasgow, in the county of Lanark, Scotland, have invented a new, original, and ornamental Design for Glass Bottles, of which the following is a specification, reference being had to the accompanying drawing, forming part thereof.

Figure 1 is an elevation of a glass bottle

showing the new design and, Fig. 2 is a plan section on the line II and partly on the line III of Fig. 1.

I claim:

The ornamental design for a glass bottle as shown.

THOMAS MACKENZIE.
